UNITED STATES PATENT OFFICE.

LOYCE D. HACKETT, OF MIAMI, FLORIDA.

DESIGN FOR A PIN.

54,913.

Specification for Design.

Patented Apr. 20, 1920.

Application filed August 8, 1919. Serial No. 316,267. Term of patent 3½ years.

To all whom it may concern:

Be it known that I, LOYCE D. HACKETT, a citizen of the United States, and a resident of Miami, in the county of Dade and State of Florida, have invented a new, original, and ornamental Design for a Pin, of which the following is a specification, reference being had to the accompanying drawing, forming part thereof.

The figure is an elevation of the pin, showing my new design.

I claim:

The ornamental design for a pin, as shown.

LOYCE D. HACKETT.
